UNITED STATES PATENT OFFICE.

LOUIS R. HORTON, OF PROVIDENCE, RHODE ISLAND, ASSIGNOR TO J. B. & S. M. KNOWLES, OF SAME PLACE.

DESIGN FOR A HANDLE FOR SPOONS, &c.

SPECIFICATION forming part of Design No. 20,595, dated March 24, 1891.

Application filed February 5, 1891. Serial No. 380,360. Term of patent 7 years.

To all whom it may concern:

Be it known that I, LOUIS R. HORTON, a citizen of the United States, residing at Providence, in the county of Providence and State 5 of Rhode Island, have invented and produced a new and original Design for Handles, of which the following is a specification, reference being had to the accompanying drawings, forming part thereof.

10 Figure 1 is an obverse view of a spoon and the handle thereof. Fig. 2 is a reverse view of the same.

The leading features of my design for handles of spoons, &c., consist in a symmetrical 15 outwardly-curving outline, increasing the width of the handle, and then curving inward and outward to the top of the handle to meet a series of small scallops forming the top edge, an oval-shaped shield traced on the handle at 20 its greatest width, floriated scroll-work traced above and below said shield and extending part way along the neck of the handle, and slightly-curving lines traced from the upper portion of the floriated scroll-work to meet 25 the small scallops forming the top edge of the handle, and which are accentuated by circular lines traced inward from the junctions of the scallops.

30 3 in the drawings designates the bowl of a spoon. It may, however, be the bowl of a ladle or the tine portion of a fork.

4 indicates the handle. The edges of the

narrow portion or neck of the handle 5 are curved outward on both sides of the handle and in opposite directions to the point 6, 35 where they commence to curve inward to 7, thence curving outward to 6', meeting the small scallops 8, forming the top edge of the spoon, from which the circular lines 8' and partially-curving lines 8 are traced inward on 40 the surface of the handle.

In the center of the enlargement 6 is traced the oval-shaped shield 9, and this shield is surrounded above and below with scrolls 10, interwoven with foliage 10', forming floriated 45 scroll-work, which also extends along the greater portion of the length of the neck 5.

The back of the handle presents the symmetically-curving outlines gradually increasing and decreasing the width of the handle to the top of the same, where they meet the scallops 8, with a line 11 traced approximately parallel to the edge and forming with the foliage 12 a border extending the length of the handle. The short circular lines 8² and 50 partially-curving lines 8⁴ are traced inward 55 from the top of the handle.

What I claim is—

The design for handles of spoons, forks, &c., as herein shown and described.

LOUIS R. HORTON.
